UNITED STATES PATENT OFFICE.

REUBEN NEIL KESTERSON, OF NEAR KNOXVILLE, TENNESSEE.

ROPE-FASTENER.

1,251,048.

Specification of Letters Patent.

Patented Dec. 25, 1917.

Application filed March 26, 1917. Serial No. 157,492.

To all whom it may concern:

Be it known that I, REUBEN NEIL KESTERSON, a citizen of the United States, residing at near Knoxville, in the county of Knox 5 and State of Tennessee, have invented a new and useful Improvement in Rope-Fasteners, of which the following is a specification, reference being had to the accompanying drawing.

10 My improvement relates particularly to devices for fastening and adjusting guy ropes used for holding tents and for other similar purposes. The object of the improvement is to provide a device which may 15 be easily applied and which will hold ropes effectively and which may be manufactured at small cost.

In the accompanying drawings,

Figure 1 is a perspective view showing a 20 guy rope and my improved fastener applied thereto;

Fig. 2 is a view looking toward the upper side of the fastener, shown in Fig. 1, the position of the rope being shown by dotted 25 lines;

Fig. 3 is a view of the opposite side of the fastener, the rope being omitted;

Fig. 4 is an edge view of the fastener;

Fig. 5 illustrates another manner of securing the rope;

Fig. 6 shows a sheet metal blank from which the fastener is formed.

Referring to said drawings, A is the body of the fastener, and B is the rope.

35 For convenience in description, the side of the body shown by Figs. 1 and 2 will be regarded as the upper side of the plate, and the right-hand end is called the "outer" or "free" end while the left-hand end is called 40 the "inner" or "fulcrum" end.

The body is formed of metal and it is flat and elongated and has the long edges, A¹ and A². Between its ends, and preferably nearer one end than the other, the body has 45 a rope-engaging device which is to receive and engage the adjacent end of the guy rope. In the form shown by the drawings, said engaging member is a lateral extension, D, in which is an eye, C, through which the rope 50 extends. Said extension is preferably turned into a plane which is perpendicular to the plane of the body, in order that the portion of the rope extending away from said eye will be below the plane of the plate.

55 On the left-hand end of the body are three

tongues. The tongue, E, is at the edge, A¹. Said tongue is curved upward and toward the opposite end of the body. The tongue, F, is at the opposite edge (the edge, A²) of the body and extends toward the left, parallel to the edge, A², without bending. Between the tongues, E and F, and adjacent the latter is the tongue, G. This is curved upward and away from the body. The tongues, E and G, are separated by a space 65 which is somewhat wider than the thickness of the rope.

At the opposite or right-hand end of the body and on the edge, A², is a tongue, H, which rises from the body and then extends 70 toward the opposite edge of the body.

The entire fastener is preferably made of sheet metal, the several rope-engaging members, the extension, D, and the tongues, E, F, G, and H, being integral with the body 75 of the fastener.

When made of sheet metal, the blank illustrated by Fig. 6 is cut out of a larger sheet, and then the rope-engaging members D, E, G, and H, are bent into their appropriate 80 forms.

For use, the end of the rope, B, is extended through the eye, C, and then knotted or otherwise secured to keep it in said eye. The rope is then placed around a stake or similar 85 member, I, to form a loop, B¹. Then the main part, B², of the rope is laid into the hook formed by the tongue, E, and thence into the hook formed by the tongue, G, and thence across the straight tongue, F, and 90 thence to and into the tongue, H. The tongues, E, F, and H, are to be made of such size as to rather closely engage the rope.

This operation of applying the rope is, however, not ordinarily accomplished by directly bending the rope to adapt it to the engaging members, E, F, and H, of the fastener. On the contrary, the fastener is moved as follows to cause said members to make the engagement with the rope. After 100 the rope has engaged the member, D, and the stake or similar member, I, the fastener is drawn away from the stake until the main portion, B², of the rope is straight and under suitable tension. Then the fastener is placed 105 lengthwise beneath the rope, with the tongue, H, toward the stake and with the part, B², of the rope lying between the tongues, E and G. Then the outer end of the fastener is swung contra-clockwise until 110

the engaging member, H, passes beneath the rope. Then said end is moved upward until the engaging member is opposite the rope. Then said end of the fastener is released, 5 Whereupon, in response to the stress applied by the rope to the members, E and G, the body reverses movement until the member, H, engages the rope. Then the engagement is complete. The portion of the rope 10 which lies in the member, G, is retained in said position by the member, F. Hence the member, F, may be called a "retaining" member.

The engagement of the rope by the members, E, G, and H, is entirely frictional. 15 The greater part is made by the members, E and G. This is facilitated by the bends made by the rope at each of these members.

It is also to be noted that when the fastener is turned into its final position, the members, E and G, partially fold the rope, whereby the tension of the rope is increased. It is also to be observed that while the fastener is being put through such final movement, the body of the fastener serves as a 20 lever comprising a long arm and a short arm, and the member, E, forming one pivot or fulcrum and the member, D, forming another fulcrum, the fastener ordinarily turning simultaneously on the two fulcra. With reference to either fulcrum, the long arm is between that fulcrum and the outer or free end of the body, A. This permits easy application of relatively large force to the portion of the rope engaged by the members, E 25 and G.

In Fig. 5, the end of the rope is held frictionally in lieu of being tied or knotted. The end of the rope is put farther through 40 the eye, C, and turned toward the right and then upward and over and crosswise around the body once or oftener. Then, when the fastener is swung into position beneath the part, B², of the rope for the engagement of 45 the member, H, on the part, B, of the rope, said part will press down on the turns of the rope which extends around the body, A. This causes frictional engagement between 50 said turns and the portion, B, of the rope and also between the turns and the edges, A¹ and A², of the body, A. This frictional engagement between portions of the rope and between the rope and the edges of the body, A, and between the rope and the member, D, may be made ample to prevent slipping 55 of the end of the rope. Thus a rope which is longer than necessary may be used without cutting and without shifting a knot when the distance between the stake and the 60 object to be guyed varies.

I claim as my invention:

1. The herein-described rope fastener comprising an elongated body, a rope end engaging portion, two oppositely-directed and separated rope engaging members located at one end of said body and arranged transversely to the length of the body, and a rope engaging member at the opposite end of the body, substantially as described. 65

2. The herein-described rope fastener 70 comprising an elongated body, a rope end engaging portion located between the ends of the body, two oppositely-directed and separated rope engaging members located at one end of said body and arranged transversely to the length of the body, and a rope 75 engaging member at the opposite end of the body, substantially as described.

3. The herein-described rope fastener comprising an elongated body, a rope end 80 engaging portion integral with the body on one of its long edges, two oppositely-directed and separated rope engaging members located at one end of said body and arranged transversely to the length of the body, and a 85 rope engaging member at the opposite end of the body, substantially as described.

4. The herein-described, one-piece, sheet-metal rope fastener comprising an elongated body, a rope end engaging portion, two oppositely-directed and separated rope engaging members located at one end of said body and arranged transversely to the length of the body, and a rope engaging member at the opposite end of the body, substantially 95 as described. 90

5. The herein-described, one-piece, sheet-metal rope fastener comprising an elongated body, a rope engaging portion located between the ends of the body, two oppositely-directed and separated rope engaging members located at one end of said body and arranged transversely to the length of the body, and a rope engaging member at the opposite end of the body, substantially as described. 100

6. The herein-described, one-piece, sheet-metal rope fastener comprising an elongated body, a rope end engaging member integral with the body on one of its long edges, two oppositely-directed and separated rope engaging members located at one end of said body and arranged transversely to the length of the body, and a rope engaging member at the opposite end of the body, substantially as described. 110

In testimony whereof I have signed my name this 23rd day of March, in the year one thousand nine hundred and seventeen.

REUBEN NEIL KESTERSON.
